United States Patent Office.

KNUD MARKUSON, OF GLOUCESTER, MASSACHUSETTS, ASSIGNOR TO HIMSELF AND LEONARD A. BURNHAM, OF SAME PLACE.

Letters Patent No. 70,587, dated November 5, 1867.

IMPROVEMENT IN HANDLES FOR SHIPS' PUMPS.

The Schedule referred to in these Letters Patent and making part of the same.

TO ALL PERSONS TO WHOM THESE PRESENTS MAY COME:

Be it known that I, KNUD MARKUSON, of Gloucester, in the county of Essex, and State of Massachusetts, have invented a new and useful Improvement in the Handles for Pumps of Navigable Vessels; and do hereby declare the same to be fully described in the following specification, and represented in the accompanying drawings, of which—

Figure 1 is a top view,

Figure 2 a side elevation,

Figure 3 a longitudinal section, and

Figure 4 a bottom view of a pump-handle provided with my invention.

Figure 5 is an under side view of it, as it appears with one portion, A, folded around upon the other part, B, of such handle.

The said handle, instead of being in one entire bar, as it is customary to make it, I construct in two separate parts, A B, the portion A being much longer than the part B. To these two parts A B I apply two hinges, *a b*, so made that their joint-pins *c c* may be easily withdrawn from the interlocking parts of the leaves of such hinges. One hinge I apply and fasten to one, and the other to the opposite side of each of the parts A B, the same being in manner as represented in the drawings. By removing either of the joint-pins *c c* of either hinge from such hinge, the longer part A may be turned around so as to lie alongside of that side of the shorter part B to which the entire hinge may be fixed. This enables the greater part of the handle to be moved out of the way of the boom of the vessel, or to be stowed across the railing which usually goes around the pumps of a vessel. A shouldered standard or pin, C, is hinged to the lower side of the part B of the handle. The shank *e* of the said standard C is to be inserted in a hole made in the said rail, in order that the standard and rail may support the pump-handle while in operation. The two parts A B of the handle may be connected by one hinge only, applied to the next two adjacent sides of them, a hasp and staple, a catch or lock of some kind, being applied to the opposite sides of the said two parts, in order to hold them in alignment with each other, but I prefer the additional hinge for such connection, as when two hinges are employed on opposite sides of the parts A B, an additional advantage is gained, for then the handle will be applicable to either pump, or can have its longer part A turned around against either of the two sides of the shorter part B, as circumstances may require.

A rod, D, having an eye, *f*, at its outer end, and a square or flat head, *g*, at its inner end, is arranged in a groove made lengthwise in the inner side of the part B, and is supported by and so as to be capable of being revolved in two staples, *h h*, fixed in the part B. The head of the rod enters a corresponding recess, *i*, made in the part A, such head and recess, when the former is within the latter, serving to prevent the rod from being revolved, and thus operating to preserve it in connection with the hook of the rod of the pump-piston or upper box. When, however, the part A of the handle is turned out of line with the part B far enough to withdraw the recess *i* entirely from the head of the rod D, such rod will be free to be revolved as far as may be necessary to facilitate the disengagement of it from the hook of the pump-piston.

My improvement saves the necessity of removing the pump-handle from the pump in order to stow such handle out of the way of the boom or persons on shipboard. It insures the pump-handle being in connection with the pump, and thus prevents it from being mislaid or washed overboard.

What I claim as my invention is—

The improved pump-handle, as made in two parts, A B, connected together by two hinges, or by a hinge and latching or locking devices, applied to their opposite sides, the whole being substantially as specified.

I also claim the arrangement and combination of the rotary rod, made as described, and the socket for the head of such rod, with the two handle-parts, A B, connected substantially as explained.

KNUD MARKUSON.
